UNITED STATES PATENT OFFICE.

NIKOLAS VIEHMANN, OF NEWARK, NEW JERSEY.

RADIATOR CAP.

Application filed March 13, 1922. Serial No. 543,209.

To all whom it may concern:

Be it known that I, NIKOLAS VIEHMANN, a citizen of Hungary, and a resident of Newark, county of Essex, and State of 5 New Jersey, have invented certain new and useful Improvements in Radiator Caps, of which the following is a specification.

This invention relates to an improved cap for receptacles, and is particularly adapted 10 for gasolene tanks and also for the radiators of automobiles, being constructed to permit the opening of the cap to permit liquid to be poured into and through it, and is one which can be closed or opened by a half turn, 15 and which is constructed to permit the installation of thermal indicators and the like.

The invention is designed to provide a cap of this kind which is not readily removable, that is, can only be removed after 20 tools have been used on it to remove parts thereof, and the cap is thus insured against loss or breakage, which often results from hasty unscrewing of a cap, or from dropping it if it is removed while it is hot.

25 The invention is illustrated in the accompanying drawings, in which Figure 1 is a central vertical section through a cap made according to my invention, and Figure 2 is a similar section taken at right angles to 30 Figure 1. Figure 3 is a section on line 3—3 in Figure 1. Figure 4 is a face view of a gasket used in the cap. Figure 5 is a top view of the cap partly open. Figure 6 is a central section of a cap of 35 modified construction. Figure 7 is a top view of the cap shown in Figure 6, and Figure 8 is a top view of a flap used in the cap shown in Figures 6 and 7.

40 For the purpose of clearly describing the invention I have illustrated and described it primarily as designed for an automobile radiator, and in the drawings 10 indicates the inlet pipe, which is the usual pipe set on top of the radiator and into which water is 45 poured when the radiator is to be filled, the pipe 10 having a screw-thread 11 which can receive the ordinary cap for a radiator, but which is also adapted to receive my improved cap, which consists of an inner mem- 50 ber 12 fastened to the top of the pipe 10, usually by having it provided with screw- threads that fit over the screw-threaded portion 11, and which is held in place by a suitable locking means, such as the lock screw 55 13.

The inner member has an opening 14 of

substantially the same size as the inner diameter of the pipe 10, and it has an enlarged portion 15 from which extends the inwardly extending web 16, the web 16 extending 60 part way across the member, preferably slightly more than half way across, in the drawing the edge 17 indicating the end of the web, so that there is thus formed an opening 18 through the web which is of any 65 desired form, but is preferably made approximately semi-circular.

The top member 19 is rotatably arranged 70 on the member 12 and is usually secured thereon by being screw-threaded. The screw-threaded portion 20 screws onto the screw-threads on the outside of the enlarged portion 15, the top member 19 having a top plate 21 provided with an opening 22 which is substantially semi-circular, which opening is adapted to be placed in and out of register with the opening 18 as the top member 75 is turned so that it either can be in position to fully open the opening 18 or to entirely close it.

I arrange a suitable gasket 23 on the under face of the top plate 21, and in the form shown the gasket is held in position by the screw 24, the gasket fitting around underneath the top plate, as will be evident from 80 Figures 1 and 2, and resting on the web and also on the enlarged portion 15, having a cut away portion 25 of the same size and shape as the opening 22.

When the device is assembled, the top 90 member is screwed down on the inner member until it has arrived at its proper position, and then its rotation in either direction is limited by a suitable means, the means shown consisting of a pin 26 which has a 95 reduced end 27 that fits in a groove 28 in the inner member, the pin or screw 26 being cut off flush with the outer face of the rim of the top member 19 and being only removable by being drilled or otherwise intentionally 100 removed.

The removal of the cap from the tube 10 is 105 guarded against by providing the top member with an apron or flange 29 which extends down far enough to cover the inner member and also the lock screw 13 so that the lock screw can not be removed.

It will be evident that when the device is to be opened to pour water into the radiator, the top member is turned until the openings 18 and 22 are in register, and then water can be poured through these aligned open-

ings into the pipe 10. The alignment of the openings 22 and 18 is easy when the pin 26 and the slot are disposed so that the pin is at one end of the slot when the cap 5 is open. When the cap is to be closed it is given a half turn until the pin gets to the other end of the slot, but it will be evident that this half turn is to the right, and the screw-threaded connection 20 is a 10 right hand thread, so that as the top member is turned it is slightly forced down by the time the half turn is completed, the edge 30 of the gasket 23 is pressed down tightly over the top face of the web, as at 31, closely 15 adjacent to the edge 17 of the web, and a water-tight and dust-tight closure is the result.

The gasket is made of substantially stiff material, such as fibre, and retains its position flat against the under face of the top plate 21, of the top member 19, and since the action of the edge 30 on the edge 17 is similar to that of a shear, there is no abutting of these edges and the edge 30 rides 25 up over the top face, but tightly against this top face, of the web 16. This provides a chamber or space within the cap when the cap is shut, so that this cap is adapted to receive and also permit the operation of 30 any of the usual indicators, one of which is shown in dotted outline at 32 in Figures 1 and 2, being fastened by suitable securing means, such as the screw 33 which passes through the hub 34 of the top member and 35 is secured to the bottom of the top member, the edge of the web having a notch 35 to allow for the head of the screw or similar element which fastens the device in place, which also allows the temperature of the 40 inside of the cap to be effective on such indicator.

Figures 6, 7 and 8 show a cap that can be adapted to a gasoline tank or the like, the inner member and the top member operating similarly to open and close the cap, the top member 19 being provided with a flap 36 which is hinged, as at 37, to the top member and is adapted to close the opening 22, any suitable means, such as a spring 45 38, being used to hold the flap shut, and the projecting finger-piece 39 providing a

means for convenience in opening the flap. The reason for covering the opening is to prevent dirt and dust settling on the web 16 through the opening 22 when the cap is 55 shut, since in this closed position the top face of the web 16 would be otherwise exposed, and if dirt did so settle on the web it would be swept therefrom when the top member is swung to open position by the 60 edge 30 of the gasket and would thus be deposited into the receptacle. The flap keeps the web clean and there is no chance of dirt or other foreign matter being deposited into the gasoline or other contents of the tank. 65

It will be evident that changes can be made in the construction and form of the parts without departing from the scope of my invention.

I claim:

1. A radiator cap comprising an inner member with a central opening and having a web on the top, the web having an opening therein, a top member comprising a top plate and having a flange in screw-threaded engagement with the inner member, and having an opening in the top plate, and a gasket secured to the under side of the top plate, and bearing on the web and having an opening in register with the opening in 80 the top plate.

2. A radiator cap comprising an inner member with a central opening and having a web on the top, the web having an opening for substantially half its area, a top member 85 having a top plate and having a flange in screw-threaded engagement with the inner member, and having an opening to register with the opening in the web, coating means on the members for limiting the rotation of 90 the top member, and a gasket on the under face of the top plate and forced into engagement with the web by the screw-threaded connection of the members when the top member is turned to place the openings in 95 the members on opposite sides of the center, the gasket having an opening in register with the opening in the top plate.

In testimony that I claim the foregoing, I have hereto set my hand, this 10th day of 100 March, 1920.

NIKOLAS VIEHMANN.
